NATHANIEL L. BRADLEY AND JOHN A. EVARTS, OF WEST MERIDEN, CONNECTICUT,
ASSIGNORS TO BRADLEY AND HUBBARD, OF SAME PLACE.

Letters Patent No. 83,246, dated October 20, 1868.

IMPROVEMENT IN GAS-FIXTURE.

The Schedule referred to in these Letters Patent and making part of the same.

To all whom it may concern:

Be it known that we, NATHANIEL L. BRADLEY and JOHN A. EVARTS, of West Meriden, in the county of New Haven, and State of Connecticut, have invented a new Improvement in Cast-Metal Gas-Fixtures; and we do hereby declare the following, when taken in connection with the accompanying drawings, and the letters of reference marked thereon, to be a full, clear, and exact description of the same, and which said drawings constitute part of this specification, and represent, in—

Figure 1, a side view,

Figure 2, a vertical central section,

Figure 3, a transverse section on line $x-x$, and in

Figure 4, an end view, to illustrate the construction of that part of the fixture, and the manner of attaching the same.

This invention is designed for the construction of gas-fixtures from cast-metal, the object being to overcome the necessity of casting the metal around the pipe, or casting it in parts, as has been done, leaving an open and irregular joint where the two parts come together; and the invention consists in casting the one part with a lip or flange, so as to project over the other part; the said lip, while it covers the joint, serving as a part of the ornamentation of the fixture; also in forming the coupling between the fixture and the pipe with a square or angular flange, so as to fit in a corresponding square or angular recess in the fixture, so that the fixture may be screwed on to its proper position without the aid of a wrench.

In order to the clear understanding of our invention, we will proceed to describe the same as illustrated in the accompanying drawings.

A is the one part, B the other part of an ordinary bracket, dividing at the centre, and so as to enclose the pipe C, as seen in figs. 2 and 3. The part A is cast with a lip, a , upon each side, and so as to form a shoulder, d , beneath which lip, and against the shoulder, the part B sets, as seen in fig. 3, and when so set together

the two parts are secured by screws D and E, as seen in fig. 1, inserted in such manner as to add rather than detract from the general configuration of design.

Thus it will be seen that, although the joint at the shoulder d may be very irregular, yet the lip a covers the joint, and forms a rib at the centre of the fixture, which, while it so covers the joint, forms an important part in the design of the fixture, and by this construction the pipe may be fitted, and the parts placed over the pipe and secured, without in any manner interfering with the joints in the pipe.

In order to facilitate the attachment of the fixture, so that the fixture itself will form the wrench by means of which it is screwed into place, we form a square or angular recess, P, within the two parts, and on the coupling R we form a corresponding square or angular flange, f , (see figs. 2 and 4,) so that when the said coupling is screwed on to the pipe C, the flange will set into and fit the recess P. Therefore, when the two parts are secured together, the recess P forms the wrench by which the pipe may be screwed to place, without the aid of the ordinary pipe-wrench.

We do not wish to be understood as broadly claiming the casting of two parts in metal, so that when the two are placed together the joint will be covered, confining our invention entirely to the manufacture of gas-fixtures.

Having fully described our invention,

What we claim as new and useful, and desire to secure by Letters Patent, is—

As an article of manufacture, gas-fixtures, the shell or ornamental part of which is formed of two parts of cast-metal, one part being provided with a lip or lips, a , to cover the joint and form a rib, substantially as and for the purpose specified.

NATHANIEL L. BRADLEY.
JOHN A. EVARTS.
